UNITED STATES PATENT OFFICE.

ISAAC ERWIN McELROY, OF MUSCATINE, IOWA.

CUT-OFF VALVE FOR ENGINES.

No. 893,188.

Specification of Letters Patent.

Patented July 14, 1908.

Application filed April 24, 1906. Serial No. 313,455.

To all whom it may concern:

Be it known that I, ISAAC ERWIN McELROY, a citizen of the United States, residing at Muscatine, in the county of Muscatine 5 and State of Iowa, have invented certain new and useful Improvements in Cut-Off Valves for Engines; and I do hereby declare the following to be a full, clear, and exact 10 description of the invention, such as will enable others skilled in the art to which it appertains to make and use the same.

The chief objects of this invention are: first, to simplify and improve the construction and increase the efficiency of operation 15 of rotary steam-valves and governing mechanism; second, to obtain by practicable means automatic control of the induction of steam or other propelling fluid, varying the cut-off according to the load, without how- 20 ever varying the counter-pressure—a result hitherto attained, it is thought, only in a Corliss engine;—also to secure sensitiveness in operation of the governor and cut-off, without impairing the accuracy or positive- 25 ness of action; third, to provide large full ports, sudden in opening and closing, thereby avoiding wire-drawing and condensation of steam by strangulation; and, further, to maintain a full open exhaust during the 30 whole of the reverse stroke of the piston, excepting as may be necessary for cushioning.

One appropriate embodiment of the invention, applied to an ordinary reciprocatory steam-engine, is illustrated in the accompanying drawings, which form a part of this specification. It is understood however that the invention is independent of the specific construction or style of engine with which it is incorporated, being adapted for general 40 application, as well as susceptible of embodiment in different forms, and of modifications in details of structure and arrangement of parts. Without restriction therefore to the particular construction illustrated, the invention will hereinafter be first fully described with reference to said drawings, and then more particularly pointed out in the appended claims.

In said drawings, Figure 1 is an enlarged 50 horizontal section through the cylinder or piston-chamber and the valve-case, showing the piston and valve in elevation, also showing a cut-off governor in section. Fig. 2 is a horizontal section through the valve, valve-case, and contiguous portion of the cylinder. Fig. 3 is a vertical cross-section on line III—

III of Figs. 1 and 2. Fig. 4 is a cross-section on line IV—IV of Figs. 1 and 2. Fig. 5 is a perspective view of the rotary valve. Fig. 6 is a face view of the cut-off governor.

60

The cylinder A, working-piston B, and piston-rod C are shown as usual in reciprocating engines.

The valve-case 1 is shown in a preferred relation, that is arranged longitudinally of 65 and beside the cylinder A. Motive fluid, steam, compressed air or the like, is supplied through the feed-pipe 2 shown in Fig. 4, which enters an intermediate part of the valve-case. Exhaust fluid is taken from op- 70 posite ends of the valve-case through the discharge pipes 3. Steam-ports 4 and 5 extend from the cylindrical valve-seat to opposite ends of the piston-chamber.

The illustrated valve, being designed to dis- 75 tribute and control the steam or other motive fluid for both sides of the piston-chamber, is therefore a double or two-part valve. It is shown comprising two valve-heads, 6 and 7, aligned and connected together, either inte- 80 grally constructed as shown, or both splined upon the same valve-rod, or otherwise rigidly united. Said valve-heads rotate in co- operative relation to the steam-ports 4 and 5 respectively. They are in the form of hol- 85 low cylinders, so constructed and internally divided by longitudinal partitions 8 as to provide in each valve-head an inlet-chamber 9 and exhaust-chamber 10. It is under- 90 stood of course that the inlet and exhaust chambers at one side are inversely arranged with respect to those at the other side, since steam is admitted to one end of the cylinder or piston-chamber while exhausting from the other end. The annular space 11 between 95

the valve-heads constitutes a medial supply-chamber, which is in constant communica- 100 tion with the feed-pipe 2. Said chamber 11 is also in open communication with the res- pective inlet-chambers 9, through ports or 105 openings 12 in the inner ends or end walls of the valve-heads. The exhaust-chambers 10 are of course closed to said medial supply-chamber 11, but are in open communication through ports or openings 13 with exhaust- 110 chambers 14 in the outer ends of the valve-case, the latter being in communication with discharge pipes 3. Thus the double valve, as a whole, is in the general form of a hollow partitioned cylinder having five chambers, viz: the medial supply 11 and the opposite inlet-chambers 9 and exhaust-chambers 10.

The outer wall or shell of each valve-head is provided with an inlet-port 15 and exhaust-port 16, open from the inlet-chamber 9 and exhaust-chamber 10 respectively, and adapted to register in alternation with the particular steam-port 4 or 5 in the valve-seat with which the particular valve-head is associated. These inlet and exhaust ports 14 and 15 are cut or formed longitudinally in the shell of the valve, and are made large or wide to maintain continuous registration with the steam-ports 4 and 5 during admission and exhaust phases of rotation of each valve-head. The valve-shaft being geared to rotate once per each rotation of the crank-shaft, the registering steam-ports are sudden in opening and closing, thereby avoiding wire-drawing and condensation of steam by strangulation. The exhaust-ports 16 are especially made wide enough to maintain a continuous full open exhaust during the reverse stroke of the piston, except as may be desired at the completion of the stroke for cushioning. In the construction illustrated, the outer shells of the valve-heads, in which the ports are formed, consist of turned sleeves fitted tightly on the circular end walls of the respective valve-heads and revolubly fitted within the valve-chamber.

30 The inlet or live-steam side of each valve-head is provided with an automatic variable cut-off device, revolving with the valve, and connected with a governor operated by the speed of the engine to control the induction of steam in such manner as to secure uniformity of speed. In the form shown, the said riding or revolving cut-off is an internal segmental plate 17, movably or slidably fitted under the shell of the valve-head at the cut-off or rearward side of the inlet-port 15 thereof, and carrying at its front or advancing edge a flange or lip 18, the latter being movably arranged in the said inlet-port or between the ends of said port and having an outer convex surface co-cylindrical with the surface of the valve-head. Hence the passing of the flange or lip 18 over the steam-port 4 or 5 in the valve-seat determines the period of cut-off, or terminates the induction of propelling fluid, allowing the propelling fluid thereafter to act expansively. Said cut-off device 17 is carried by a radially arranged spider or support 19, co-axial and revoluble with the valve-head, but capable of a variable relation thereto. The cut-off device is preferably freely or loosely mounted on said spider or support 19, as by pin and slot fastenings 20, or by other suitable means, whereby the riding cut-off is always properly seated by pressure of steam on the inner or end face of the segmental plate 17.

As shown, the spiders or supports 19 for the two cut-offs are keyed or fixed on a shaft 21, which is revolubly arranged in the center of the valve, within a hollow valve-shaft 22, the latter being keyed or fixed to the valve. The said cut-off shaft 21 passes out through said valve-shaft 22 beyond one end of the valve-case. The valve-shaft 22 may be either an independent hollow shaft, as shown, or it may be an extension of the valve-rod proper 23, which is shown extending out through the opposite end of the valve-case. The cut-off may be controlled by any suitable device, as by means of a speed-governor or other mechanism operating on the cut-off shaft 21. For example, in the case of a locomotive engine, a lever may be employed to control the variable cut-off. However, as a part of my invention, I have devised the construction now to be described, in which is employed a speed-governor revoluble with the valve and operatively connected with the cut-off shaft. On the end of said hollow valve-shaft 22 is a centrifugal governor 24, of any suitable type or construction, which is connected with the cut-off shaft 21 in such manner as to rotate the same, with the valve-shaft, but at a variable relation thereto, according to the speed of the engine. Hence any variation in speed causes a variable relative position of the shafts 21 and 22, thereby moving the riding cut-off device, so as to lengthen or shorten the period of admission. The illustrated governor comprises a disk or element mounted on the valve-shaft 22, and carrying spring-connected weighted levers 25, which are connected by links 26 with a yoke or cross-piece 27 to the cut-off shaft 21, thereby making a yielding connection between the shafts adapted to turn them together but allowing a variation in their relative positions under the centrifugal action of the weights. The governor being thus directly and closely connected with the cut-off, has its sensitiveness greatly increased without impairing its positive action. It will be noted, moreover, that the variations in the periods of admission, due to the action of the governor and riding cut-off, does not affect the counterpressure, since the cut-off is varied by a restriction of the width of the inlet-ports 15, without however varying the position of the valve itself, nor varying the position or the size of the exhaust-ports 16, which latter maintain a full open exhaust for the reverse stroke of each side of the piston.

The valve may of course operate two or more cylinders as well as one cylinder, in which instance the valve-case would be arranged between the cylinders, steam-ports being provided for the respective cylinders, each for successive registration with the inlet and exhaust ports of the valve.

Having thus fully described my invention, what I claim as new and desire to secure by Letters Patent of the United States is:—

1. In rotary valve mechanism, the combination of a cylindrical valve-case having a lateral port, a rotary valve therein compris-

ing a hollow cylindrical head having lateral admission and exhaust ports adapted to register with the port in said valve-case, and a variable riding cut-off carried inside said valve and seated by steam pressure against the interior of the valve-case.

2. In rotary valve mechanism, the combination of a cylindrical valve-case having a lateral port, a rotary valve therein comprising a hollow cylindrical head having lateral admission and exhaust ports for registering with the port in said valve-case, a governor-operated shaft arranged coaxially in said valve and movable therewith, and an internal riding cut-off mounted on said shaft comprising a loosely held segmental plate fitted under the cut-off side of the admission port and having a flange or lip fitted within said admission port against the interior of the valve-case, said cut-off being seated by steam pressure.

3. In rotary valve mechanism, the combination of a cylindrical valve-chamber having a port therein, a hollow rotary valve fitted in

said chamber and having a coöperative inlet-port, a variable cut-off device revolvable with the valve and movably arranged in the inlet-port thereof, said cut-off device having an outer surface flush with the interior walls of the valve-chamber and being freely or loosely held, and seated by pressure of motive-fluid in the valve.

4. A rotary valve comprising a hollow cylindrical shell having a lateral inlet-port, an independently-turnable rod or shaft axially arranged therein, a radially-arranged spider or support on said rod, and a riding cut-off device carried by said spider, said device comprising a segmental plate fitted under the inner wall of the valve-shell at the cut-off side of its port and being loosely fastened on said spider.

In testimony whereof I affix my signature, in presence of two witnesses.

ISAAC ERWIN McELROY.
